UNITED STATES PATENT OFFICE.

LUDVIG S. WALLE, OF SCOTIA, NEW YORK, ASSIGNOR TO GENERAL ELECTRIC COMPANY, A CORPORATION OF NEW YORK.

CENTRIFUGAL MECHANISM FOR ELECTRIC SWITCHES AND OTHER APPARATUS.

Application filed June 8, 1922. Serial No. 566,915.

My invention relates to new and useful centrifugal mechanisms and more particularly to improvements in operating devices adapted for use with electric switches and other apparatus, and has for an object to provide a simple, efficient and durable operating device operable by either alternating or continuous current or other power arranged to provide rotary motion, to produce maximum effort and speed in operation without mechanical shocks and with minimum power consumption.

Another object of my invention is to provide an operating device in which the force developed increases as the operation progresses and is automatically adjusted by the mechanical load or the resistance offered by the apparatus to be operated, and in which is stored energy that is instantly available to overcome the load so that prompt and certain operation of the apparatus to be operated is assured.

A further object of my invention is to provide an operating device which has a definite and accurate range of operation or travel, and in which the action is automatically stopped at the end of the operating range to prevent over-travel.

A still further object of my invention is to provide an operating device which may be operated by an ordinary electric motor of relatively small size and which may be applied with very slight changes to replace existing types of operating devices to obtain better operation without necessitating complete and costly reinstallation.

My invention will be better understood from the following description taken in connection with the accompanying drawings, and its scope will be pointed out in the appended claims.

Figure 1 is a side elevation of an embodiment of my invention associated with an oil circuit breaker shown in circuit closed position; Fig. 2 is a detail of a hand operating lever; Figs. 3, 4 and 5 are sectional elevations illustrating thrust bearing and connection details of the embodiment of my invention shown in Fig. 1, Fig. 5 being a section perpendicular to the section shown in Fig. 4; Fig. 6 is a view in perspective illustrating parts of the device shown in Fig. 1; Fig. 7 is a side elevation similar to Fig. 1 with the parts of the operating device shown in the circuit open position of the circuit breaker, not shown, and ready to be operated to close the circuit breaker; Fig. 8 is an elevation taken perpendicular to the elevation shown in Fig. 7; Fig. 9 is a fragmentary rear side elevation of the mechanism when in the position shown in Fig. 7; Fig. 10 is a top plan view of Fig. 9; Fig. 11 illustrates diagrammatically a system of control for the embodiment of my invention shown in Fig. 1; Fig. 12 is a detail illustrating a control switch; Fig. 13 is a side elevation of a modification of my invention associated with a carbon break circuit breaker shown in circuit open position; Fig. 14 is a view similar to Fig. 13, except that the parts are shown in the circuit breaker closed position; Figs. 15 and 16 are side elevations taken perpendicular to each other of another modification of my invention; Fig. 17 illustrates diagrammatically a system of control embodying the form of my invention shown in Figs. 15 and 16; and Fig. 18 is a modification of the form of my invention shown in Figs. 1, 7 and 8.

In Fig. 1, I have illustrated an embodiment of my invention applied to an electric switch, such as a circuit breaker 1, which may be of a type having relatively movable cooperating contacts biased to circuit opening position and separable in an insulating fluid, and which is shown in this figure in circuit closing position. The circuit breaker 1 is mounted on a suitable supporting structure 2, and is arranged to have its contacts controlled by any suitable operating mechanism, such as that illustrated, which comprises a movable crosshead 3 carrying the movable contacts, a lever 4, a toggle comprising links 5 and arranged to be underset with the circuit breaker 1 in circuit closing position, and a connecting link 6 which is preferably adjustable to render the operating mechanism adaptable to circuit breakers differing in capacity, size or throw, and which may embody a trip-free or collapsible mechanism. The type of trip-free mechanism which may be used is immaterial so far as my invention is concerned, the trip-free mechanism shown for purposes of illustration being of the type disclosed in Patent No. 1,421,740 to Harry M. Stevens, switch mechanism, July 4, 1922, and assigned to the same assignee as this invention. This collapsible or trip-free mechanism comprises a link 7, which has one end slidably mounted in the connecting link 6 and which is pivot-

ally associated with a link 8 which is pivoted to the link 6. The links 7 and 8 form a toggle arranged to be held in rigid or thrust-transmitting position, under set in the example shown, by a latching member 9 which engages link 7 and a latching member 10 which engages link 8 and is pivoted to latching member 9, a stop on the link 8 abutting the link 6.

10. For the purpose of actuating the operating mechanism to control the circuit breaker, I provide in accordance with my invention, associated with the operating mechanism, a centrifugal device arranged upon rotation thereof to exert a force on the operating mechanism proportional to the speed of rotation of the centrifugal device. The centrifugal device comprises a frame 11, which may be provided with lugs or bosses 12, whereby the device may be secured to a suitable supporting structure. Supported by a bracket 13, which is secured to the frame 11, is a rotatable member or rotating head 14, and mounted for movement relatively thereto is an operating member 15, one end of which is connected to a pin or shaft 16 forming a cross-head slidably mounted on the rotating head 14. For moving the operating member 15 relatively to the rotating head 14, I provide means for exerting on the operating member 15 a force proportional to the speed of rotation of the rotating head 14. This means comprises weights 17, pivotally associated with the operating member 15 at a point not coincident with their centers of gravity; that is to say, the weights 17 are mounted to turn about an axis, the shaft 16, which is not colinear with the centers of gravity of the weights 17, which are also pivotally associated with links 18 pivotally connected at 19 to the rotating head 14. The weights 17 and their associated links 18 thus constitute a toggle mechanism for actuating the operating member 15. The weights 17 may be homogeneous but in order to increase the centrifugal force exerted by the weights 17 without changing their size or shape, I may make the free end of the weights 17 hollow and fill them with a material of higher specific gravity than the material from which the weights are made as by so doing the construction of the centrifugal device may be made more compact. Associated with the operating member 15 is a connecting member 20 which may be an eye or clevis member, and which may be coupled to the operating member 15 by any suitable means such as the thrust bearing coupling shown in Fig. 3, and comprising bearing plate 21, balls 22, thrust plate 23, coupling sleeve 24, and coupling stud 25. The operating member 20 may be connected to the circuit breaker operating mechanism for imparting movement thereto by any suitable means, such as a crank 26, pivotally mounted on the frame 11 at 27 and pivotally associated with the operating member 15 and the connecting link 6.

For rotating the rotating head 14, I may use any suitable means adapted to produce rotary motion, such as an electric motor 28 which may be either an alternating current or a continuous current motor, and which is preferably of the type having a series characteristic such as a series type direct or alternating current motor or a repulsion induction type alternating current motor. The motor 28 is preferably secured to the frame 11, and in order that the usual type of motor may be used without modifications, the motor shaft 29 is coupled to the rotating head 14 by a thrust bearing coupling which takes up the thrust due to the centrifugal force exerted by the revolving weights 17 and supports the rotor of the motor 28 vertically so that there is no end thrust on the motor shaft 29 even from the weight of the rotor. One way of providing these desirable features is illustrated in detail in Figs. 4 and 5, which show a universal thrust bearing coupling which is arranged to be mounted on the bracket 13. This coupling comprises, between the bracket 13 and the rotating head 14, a collar 30 on which the rotating head 14 and its associated parts bear when the parts are at rest in the position shown in Fig. 7, upper and lower universal thrust plates 31, 32, respectively, balls 33, a bearing plate 34, a lubricant retainer 35, a coupling sleeve 36 secured to the rotating head 14, and a coupling hub 37 secured to the motor shaft 29 and interlocking with the coupling sleeve 36 and secured thereto for relative movement by studs 38.

For the operation of the embodiment of my invention so far described, it will be assumed that the parts are in the circuit-breaker closed position shown in Fig. 1; and that the motor 28 is not energized. It will be obvious that the bias of the circuit breaker operating mechanism to circuit opening position tends to turn the crank 26 counter-clockwise on its pivot 27, thus tending to cause the operating member 15 to move up. To overcome this tendency for the operating mechanism to move to circuit opening position, the toggles comprising weights 17 and links 18 are arranged to be overset in the circuit closing position as shown in Fig. 1, and to be restrained in the overset position against the bias of the operating mechanism by extensions or shoulders 29 which abut or bear against the rotating head 14. With this arrangement, the circuit breaker is not automatic or trip-free, and as the trip-free feature is desirable the operating mechanism preferably comprises a collapsible or trip-free mechanism which may be of the type heretofore described. For controlling the collapsible mechanism, there is provided

a tripping member 40 arranged to be operated by one or more electroresponsive devices which may be mounted in a housing 41 on the frame 11. The electroresponsive devices may be operative in response to abnormal conditions on the circuit controlled by the circuit breaker 1, or by independent control circuits, or both. The operation of any one of the electroresponsive devices will cause a movable member 42 thereof to move the tripping member 40 to impart a sudden blow to the latching member 10, thus releasing latching member 9 and causing the toggle comprising links 7 and 8 to collapse and move to circuit opening position. The restraint tending to hold the toggles comprising weights 17 and links 18 overset is thus removed, and the weights 17 throw the toggles over center and turn to the position shown in Figs. 7 and 8. The weights 17 may be accelerated in this movement by any suitable means such as a torsion spring 43 mounted on the shaft 16 and torsioned as the weights 17 are raised. The position of the weights 17 in the circuit open position of the circuit breaker 1 is, of course, dependent upon the throw of the circuit breaker, that is to say the travel of the operating member 15 so that a given centrifugal mechanism is adapted to operate circuit breakers having different throws by adjusting the connecting link 6. For resetting the trip-free mechanism during the circuit opening movement, the crank member 26 is pivotally associated with toggle link 8 and is preferably biased or counterweighted to turn counterclockwise on its pivot 27 so as to insure that the toggle comprising links 7 and 8 is reset.

Where a centrifugal device is used as an actuating means and the weights thereof pivoted to swing outwardly to move the switch the weights approach a position, due to the changing angle, where the centrifugal force thereof becomes less and less effective. This is an undesirable condition, however, since after the contacts of the switch begin engagement the additional frictional resistance thereof must be overcome. Compensation for the loss in effectiveness of the weights as they swing outwardly is afforded by the toggle mechanism illustrated which as will be noted from the drawing is moved by the weights from the buckled or less effective position to the straightened position where the weights more effectively transmit their force to the switch.

For controlling the operation of the centrifugal device and the circuit breaker, I provide a system of control shown diagrammatically in Fig. 11 and embodying a switch comprising relatively movable cooperating contacts 44 and 45 arranged to be closed when the circuit breaker is open, and open when the circuit breaker is closed, in response to the movement of the operating member 15 with which the contact 45 is operatively associated by means of links 46 and 47. In Figs. 7 and 8, and as shown in detail in Fig. 12, the contact member 44 is in circuit closed position, while in Fig. 1 it is in circuit open position. The control system illustrated in Fig. 11 comprises a control bus 48 to which may be connected by a switch 49 the motor 28 when the contact member 45 is in circuit closed position, or an electroresponsive device 50 as heretofore pointed out arranged to actuate the tripping member 40. Assuming now that the parts of the centrifugal device and operating mechanism are in the position shown in Figs. 7 and 8, that is to say the circuit open position of the circuit breaker, not shown, and it is desired to close the circuit breaker, the operation will be as follows: Since contacts 44 and 45 are in circuit closing position, movement of the switch 49, see Fig. 11, to the lower contact controlling position will complete the circuit of the motor 28. The motor being energized will rotate the rotating head 14, thus causing the weights 17 to fly out under the action of the centrifugal force generated and causing the members 17 and 18 comprising the links of the toggle mechanism to move from the collapsed or buckled position shown in Fig. 7 to the straightened and slightly overset position shown in Fig. 1. The operating member 15 is thus pulled downward without shocks or jars by a force which varies with the speed of rotation of the rotating head 14, and which is inherently adjusted to the load or resistance offered by the circuit breaker operating mechanism or apparatus to be operated. Consequently, at a predetermined speed of rotation of the rotating head 14, the circuit breaker will be closed and the toggle mechanism comprising weights 17 and links 18 set in rigid or thrust transmitting position to hold the operating mechanism in circuit closing position. Just prior to the final closing movement of the operating mechanism, the contact member 45 will be moved out of engagement with contacts 44 by the movement of the operating member 15, and the circuit of the motor 28 will be interrupted. Obviously, the weights 17, due to inertia, will tend to revolve for some time after the motor 28 is deenergized, and consequently if the circuit breaker 1 were closed on an overload or short circuit it would not open instantly unless the operating mechanism were trip-free as illustrated. Also, if the circuit is closed on an overload or short circuit and is opened instantly in response to the electroresponsive protective devices, it will be necessary to wait for the weights 17 to come to rest and drop to the position

shown in Figs. 7 and 8 before the centrifugal device can be operated to close the circuit breaker a second time. In order to overcome this difficulty, I may provide suitable means for stopping the rotation of the rotating head 14 when the motor 28 is de-energized, as illustrated in Fig. 18. This means may comprise a braking member 51 secured to the frame 11 and having a braking surface which may be lined with suitable material 52 and which is arranged to engage the revolving weights 17 to retard their movement so as to bring them quickly to rest. With this arrangement it is unnecessary to provide the links 18 with shoulders 39 to hold the toggle mechanisms comprising links 18 and weights 17 overset against the bias of the operating mechanism, as the braking member 51 will not only retard the revolution of the weights, but will also restrain them to hold the toggles 17, 18 in thrust transmitting position.

For protective purposes, I provide a readily removable housing or cover 53 arranged to enclose the centrifugal device and adapted to engage the frame 11 so as to be quickly and easily removable therefrom for inspection, lubrication, and repairs when necessary. As an additional safety feature for protection in the event that the weights 17 break loose while being revolved, I provide a safety band or belt 54 surrounding the space in which the weights 17 are revolved and secured to the frame 11 independently of the cover 53 so that the cover 53 can be removed without removing the safety band 54. For this purpose, the safety band 54 is preferably external to the cover 53 and spaced apart therefrom. With this construction, it will be evident that in the event of the weights 17 coming loose the cover 53 will first act to stop their movement and in the event of the cover 53 failing under the stress of the shock caused by the weights 17, the comparatively heavy safety band 54 will act to stop further movement of the weights.

For hand operation, the crank 26 may be provided with a pocket 55 arranged to be engaged by a band operating lever 56, see Fig. 2, by means of which the operating mechanism of the circuit breaker can be moved to circuit closing position. To hold the operating mechanism in circuit closing position, a latch or hook member 57 is provided which is mounted on the frame 11 and is movable into a pocket or hole 58 in the crank 26 to restrain the same in the position shown in Fig. 1.

It will be evident that after closing the motor control switch 49, see Fig. 11, that an appreciable time may elapse before the inertia of the weights 17 is overcome and they have gained sufficient speed of rotation to close the circuit breaker. This time is

very short and with the usual circuit closing operations, a fractional horse power motor will operate to close a circuit breaker of relatively large capacity as quickly as desired. However, in certain operations, such as synchronizing, it is desirable to have the circuit closing operation under definite control with respect to the time factor. For conditions such as this, I have provided the mechanism with the means illustrated by Figs. 9 and 10 whereby the weights 17 are restrained in the position shown in Fig. 7 while being accelerated so that when released they will close the circuit breaker substantially instantaneously. For this purpose, I may provide means for restraining the operating member 15 and therefore its associated parts in the circuit open position, comprising a toggle whose links 59 and 60 are pivotally associated with the frame 11 and the crank 26, respectively, and with each other and which is arranged to be held in rigid or thrust transmitting position against the force the revolving weights 17 tend to exert, the link 60 having a stop 61 abutting the link 59 in an overset position in the arrangement illustrated. For tripping the toggle 59, 60 to allow the weights 17 to fly out after they have been accelerated, I provide an electroresponsive device 62. For controlling the device 62, I connect it to the control bus 48 through a switch 65. In the operation of the centrifugal device, the operator closes the switch 49 and allows the motor 28 and weights 17 to get up to the maximum speed. Then when conditions are right for synchronizing, as indicated by a synchroscope or other synchronizing device, the switch 65 is closed thus energizing the electroresponsive device 62 which trips the toggle 59, 60, whereupon the rapidly revolving weights 17 fly out and close the circuit breaker substantially instantaneously. The accelerating period is thus done away with and the operator knows definitely when it is safe to allow the centrifugal device to close the circuit breaker.

In Figs. 13 and 14, I have illustrated a modification of my centrifugal device associated with a carbon break circuit breaker arranged to be operated in accordance with my invention and shown in Fig. 13 in circuit open position and in Fig. 14 in circuit closed position. The circuit breaker is mounted on a suitable supporting structure 66 and comprises fixed primary contacts 67 adapted to be bridged by a movable contact member or brush 68. The circuit breaker may also comprise cooperating secondary and tertiary contacts 69 and 70 for breaking the arc upon the opening of the circuit breaker. The brush 68 is secured to a brush lever 71 pivotally associated with the circuit breaker frame 72 and arranged to be actuated by an operating mechanism comprising links 73

5 pivotally associated with the frame 72 and with an operating link 74, pivotally associated with the brush lever 71. The links 73 and operating member 74 form a toggle mechanism arranged to be underset in circuit closing position and to be biased to circuit opening position. For holding the operating mechanism in circuit closing position, the operating link is provided with a 10 catch 75 arranged to be engaged by a latching member 76 which is adapted to be operated in a well known manner by an electro-responsive device 77 associated with the circuit breaker frame 72 and arranged to trip 15 the latching member 76 which may also be manually tripped.

For actuating the circuit breaker operating mechanism, I provide a centrifugal device associated therewith and differing in 20 some respects from the modification of my invention illustrated in Fig. 1. This centrifugal device comprises a rotating head 14' and an operating member 15' having one end thereof pivotally associated with a cross-head or shaft 16' slidably mounted on the rotating head 14'. Weights 17' are pivotally associated with the operating member 15' at a point not coincident with their centers of gravity, the weights being mounted to turn 25 on the shaft 16' and provided with slots 78 which, when in alinement as illustrated in Fig. 2, permit the operating member 15' to move relatively to the weights 17'. The weights 17' are also pivotally associated with 30 links 18' which are pivotally connected to the rotating head 14' at 19'. The weights 17' and links 18' thus form a toggle mechanism operative in response to the rotation of the rotating head 14' to move the operating member 15' relatively thereto. The links 17' are provided with shoulders or extensions 39' which abut the rotating head 14' as shown in Fig. 14 to prevent overtravel of the toggle mechanism, that is to insure the alinement of the slots 78 in the circuit closed position of the circuit breaker. For collapsing the toggle mechanism comprising weights 17' and links 18', the mechanism may be biased by any suitable means, such as springs 45 40 45 50 55 60 65 70 75 80 85 90 95 100 105 110 115 120 17 will, as the weights fly out, increase quite rapidly at first but at a decreasing rate as the centers of gravity of the weights approach a horizontal plane through the axis of the shaft 16. It will also be evident that the lever arm of the centrifugal force with respect to the pivotal connections of the links 18 and weights 17 as axes of moments will, as the weights 17 fly out, decrease rather slowly at first but at an increasing rate. Consequently, the torque due to the centrifugal force tends to maintain itself more or less unchanged in value. The resistance or force on the operating member 15 due to the bias of the operating mechanism tends to decrease somewhat as the contacts are moved towards engaging position and then to increase rapidly as the contacts touch and are closed. The lever arm of this force with respect to the same axes of moments as before, however, decreases quite rapidly as the toggles 17, 18 are straightened and the pivotal connections of the links 18 and weights 17 approach the axis of rotation of the rotating head 14. Consequently the countertorque opposing the torque exerted by the centrifugal force is easily overcome since the toggles 17, 18 provide a mechanical advantage tending to decrease the countertorque to the advantage of the torque due to the centrifugal force exerted by the weights 17. By means of my invention, therefore, it is possible to operate electric switches with a power consumption which is exceptionally small as compared with prior operating devices and particularly solenoid operated devices, especially when these are operated by alternating current. For example, in a practical installation of the modification of my invention illustrated in Fig. 1, a 6000 kv.-a. capacity oil circuit breaker has been successfully operated with a one-fourth horse-power repulsion induction type electric motor on a 220 volt alternating current control circuit with a 20-ampere starting current to close the circuit breaker in less than one-half a second from the instant the motor is energized. In the modification of my invention shown in Figs. 13 and 14, a one-eighth horse-power or even smaller motor is sufficient to operate a circuit breaker of the type illustrated.

In Figs. 15, 16 and 17, I have illustrated a modification of my invention embodying a centrifugal device which is arranged upon rotation in one direction to impart linear motion in one direction to an operable member and restrain the same in a predetermined position at the end of its movement and upon rotation in the opposite direction to release the operable member. Referring first to Figs. 15 and 16, this modification of my invention comprises a centrifugal device including a rotatable member or ro-

tating head 80 which for the purpose of being rotated may be coupled to the shaft 81 of an electric motor 82. Pivotaly associated with the rotating head 80 are weights 83 on axes, such as pins 84, not colinear with the centers of gravity of the weights 83 which are mounted to slide freely on the pins 84, that is to say to move longitudinally of the pins 84 and for free and easy movement roller bearings may be used. The weights 83 are pivotally associated with links 85 which are pivotally associated at 86 with a connecting member 87 to which may be coupled by a suitable thrust bearing coupling such as illustrated in Fig. 3, for example, an operating member 88 which may be connected to the operating mechanism of an electric switch or other apparatus for controlling the operation thereof. For locking the centrifugal device in the position shown in dotted lines in Fig. 16, that is to say in the circuit closed position, I provide suitable means associated with the operating head 80, such as a projection or pin 89 against which the face of the supporting arm of one of the weights 83 is arranged to bear and slide over when the weights 83 are revolved counterclockwise looking up towards the motor, due to the inertia of the weights 83 and the air resistance offered to their revolution.

In Fig. 17, I have shown a control system embodying the features of my invention shown in Figs. 15 and 16. In Fig. 17 the motor 82 is arranged with its field 90 connected to a control bus 91 while the rotor is arranged to be connected to the bus 91 through a double throw switch 92 arranged to reverse the direction of current in the rotor so as to change the direction of rotation of the motor. In the circuits controlled by the switch 92 are auxiliary switches 93, 94, one of which, 93, is arranged to be closed when the electric switch controlled by the centrifugal device is open and open when the electric switch is closed and the other of which, 94, is arranged vice versa. These switches may be operated in a manner and be of the same construction as illustrated in Fig. 12 with the exception that the switch 94 should operate instantly to open the circuit in which it is included, whereas the switch 93 is identical with that shown in Fig. 12 and opens the motor circuit only near the end of the circuit closing movement of the electric switch controlled by the centrifugal device.

Referring now to the operation of the modification of my invention shown in Figs. 15, 16 and 17, it will be assumed that the parts are in the full line position shown in Figs. 15 and 16. The switch 92, Fig. 17, is thrown to the left which completes a circuit through the closed auxiliary switch 93 and the rotor of the motor in one direction

which it will be assumed causes the motor 81 to rotate clockwise looking down on the motor in Figs. 15 and 16. The weights 83 immediately begin to fly out under the centrifugal force generated and are prevented from sliding to the right on pins 84 as shown in Fig. 15 by the pin 89 against which the supporting arm of one of the weights 83 bears until the weights have moved sufficiently to clear the pin 89. The inertia of the weights 83 and the air resistance offered them then causes the weights 83 to slide on the pins 84 in a direction opposite to their direction of revolution and the pin 89 engages the weights 83 as shown in the dotted line position in Fig. 16 and prevents the weights 83 from dropping thus restraining the operating member 88 in circuit closing position. As the weights 83 approach the position shown in dotted lines, the auxiliary switch 93 opens the circuit of the motor and the auxiliary switch 94 is closed. To release the centrifugal device, that is to trip the electric switch controlled thereby, the switch 92 is thrown to the right thus causing current to go through the rotor of the motor in the opposite direction thereby causing the motor to rotate counterclockwise looking down. Due to the inertia of the weights 83 they will be caused to slide on the pins 84 in a direction opposite to their direction of revolution to disengage pin 89 and the bias to which the operating member 88 is subject will pull the weights 83 down before the motor 82 has the weights sufficiently accelerated to overcome this bias. Consequently, the electric switch controlled by the centrifugal device will cause the auxiliary switch 94 to open thereby interrupting the motor circuit so that the weights are no longer accelerated and permitting the operating member 88 to return to circuit opening position.

While I have shown and described in detail several embodiments of my invention and the application thereof particularly to electric switches, it is obvious that my invention is not limited to the particular arrangements or applications described and I therefore aim in the appended claims to cover all such modifications or applications as fall within the spirit of my invention.

What I claim as new and desire to secure by Letters Patent of the United States, is:

1. An electric switch having a collapsible link operating mechanism and a centrifugal actuating means therefor, said mechanism being movable by said means from a collapsed position through a straightened position to an overset position to close the switch and being prevented from returning to the collapsed position by the reaction of the switch.

2. An electric switch having a toggle

operating mechanism, a centrifugal device for moving the toggle mechanism from a buckled position through a straightened position to an overset position to close the switch, said toggle mechanism being held from returning to the buckled position by the reaction of the switch.

3. An electric switch having a rotatable toggle operating mechanism, centrifugal weights rotatable with the toggle operating mechanism for moving the same, from a buckled position to a straightened position in response to a predetermined speed of rotation.

4. An electric switch, operating means therefor, a centrifugal device for imparting movement to said operating means to move said switch in one direction, an electric motor for operating said centrifugal device; means for preventing said centrifugal device from imparting movement to said operating means, and means for controlling said preventing means.

5. In combination, an electric switch, operating mechanism therefor, a centrifugal device for actuating said operating mechanism, and means for actuating said centrifugal device whereby the centrifugal force exerted thereby actuates said operating mechanism to close said switch, said centrifugal device comprising means for restraining said switch in circuit closed position independently of said actuating means.

6. An electric switch, operating mechanism therefor, a centrifugal device for imparting movement to said operating mechanism to move said switch in one direction, an electric motor for operating said centrifugal device, means for restraining said centrifugal device from imparting movement to said operating mechanism, and electroresponsive means adapted to be operated to control said restraining means.

7. In an operating mechanism of the class described, a member biased for movement in one direction, a centrifugal device arranged to move said member in the opposite direction, said centrifugal device comprising toggle mechanism for moving said member arranged upon a predetermined speed of said centrifugal device to take a position to restrain said member from movement in the direction in which the same is biased after the speed is reduced.

8. In an operating mechanism of the class described, a member biased for movement in one direction, a centrifugal device arranged to move said member in the opposite direction, said centrifugal device comprising a toggle mechanism whose elements are arranged to move from a collapsed relation to a straight line relation in the operation of the device.

9. In an operating mechanism of the class described, a member biased for movement

- in one direction, a centrifugal device arranged upon actuation thereof to move said member in the opposite direction, said centrifugal device comprising toggle mechanism for moving said member arranged to be overset upon a predetermined speed of said centrifugal device to restrain said member from movement in the direction in which the same is biased when said device comes to rest.
10. A centrifugal device comprising rotatable weights, a member operable thereby, and means connecting said weights and said operable member comprising a toggle mechanism having link members arranged to be moved by the weights from a collapsed position to a straightened out position.
11. An electric switch and a rotatable operating device therefor comprising a toggle mechanism having weights and operative at a predetermined speed of rotation to move the switch to closed circuit position, said switch being restrained in closed circuit position by said device independently of any reduction in speed thereof.
12. In combination, an electric switch, operating mechanism therefor, a centrifugal device for actuating said operating mechanism comprising a rotatable member, an operating member associated with said operating mechanism, a plurality of weights pivotally associated with said operating member at a point not coincident with their centers of gravity and revolvable by said rotatable member, links connecting said weights to said rotatable member, and means for rotating said rotatable member, said links and said weights forming the elements of a toggle mechanism operative in response to the rotation of said rotatable member to move from a collapsed to a straightened position for moving said operating member to actuate said operating mechanism.
13. In a device of the class described, an electric motor, a rotatable member coupled with the driving shaft of said motor, an operating member biased for movement in one direction, a plurality of weights pivotally associated with said operating member at a point not coincident with their centers of gravity, and links connecting said weights to said rotatable member, said links and said weights comprising toggles adapted upon a predetermined speed of said motor to move said operating member a predetermined distance in a direction opposite to the direction in which the member is biased and to restrain said member from movement in the direction in which the member is biased when said motor is deenergized.
14. In combination, a circuit breaker comprising relatively movable contacts biased to circuit opening position, operating mechanism for controlling said contacts, a centrifugal device for actuating said operating mechanism to move said contacts to circuit closing position comprising a rotatable member, an operating member movable relatively thereto associated with said operating mechanism, and means comprising a toggle mechanism operative in response to a predetermined speed of rotation of said rotatable member to move said operating member in a direction to actuate said mechanism to move said contacts to circuit closing position, an electric motor for rotating said rotatable member, means operative in response to a predetermined movement of said operating member to interrupt the circuit of said motor, and means for quickly bringing said centrifugal device to rest.
15. In combination, a circuit breaker comprising relatively movable contacts biased to circuit opening position, operating mechanism for controlling said contacts, a centrifugal device for actuating said operating mechanism to move said contacts to circuit closing position comprising a rotatable member, an operating member movable relatively thereto associated with said operating mechanism, and means comprising a toggle mechanism operative in response to a predetermined speed of rotation of said rotatable member to move said operating member in a direction to actuate said mechanism to move said contacts to circuit closing position, an electric motor for rotating said rotatable member, means operative in response to a predetermined movement of said operating member to interrupt the circuit of said motor, and means for quickly bringing said centrifugal device to rest upon the interruption of the motor circuit arranged to restrain said toggle mechanism from movement against the bias of said contacts.
16. An electric switch having a toggle operating mechanism and centrifugal weights for moving the toggle mechanism to an overset position in response to a predetermined speed of rotation of the weights, said toggle mechanism being retained in the overset position by the reaction of the switch.
17. In combination an electric switch, a centrifugal device for closing the switch, a releasable connection between the switch and the centrifugal device and means adapted to respond to a predetermined condition of a circuit controlled by the switch for releasing said connection.
18. An electric switch having a rotatable toggle operating mechanism and weights rotatable with the toggle mechanism, said weights being arranged to move the toggle mechanism to a buckled position when the speed of rotation is below a predetermined value and to move the toggle mechanism to a straightened position when the speed is above a predetermined value.
19. An electric switch having a rotatable toggle operating mechanism and weights

carried by links comprising said mechanism for moving the mechanism from a buckled position to a straightened position in response to a predetermined speed of rotation thereof.

20. An electric switch having a rotatable toggle operating mechanism and weights carried by links comprising said mechanism for moving the mechanism in response to a predetermined speed of rotation from a buckled position to an overset position to close the switch, said weights being arranged to return the toggle mechanism to the buckled position when in a state of rest and 15 when relieved of the reaction of the switch.

21. In combination, an electric switch, operating means therefor comprising a combined toggle mechanism and centrifugal device and a motor for rotating the operating means, said toggle mechanism having certain of its links provided with centrifugal weights adapted in response to a predetermined speed of said motor to move the toggle links from a buckled position toward a 25 straightened position.

22. In combination, an electric switch, an operating member therefor, an electric motor for actuating the member and rotatable means operatively connecting said motor and 30 said member comprising pairs of pivotally connected members forming a plurality of toggle mechanisms, one member of each pair having a laterally extending portion forming a centrifugal weight.

23. An electric switch, centrifugal means responsive to a predetermined speed of rotation for moving the switch to closed circuit position comprising weights movable with increased speed of rotation from a greater to a less effective position and means between the centrifugal means and the switch for compensating the loss in effectiveness of said weights comprising a toggle mechanism movable by the centrifugal means from a buckled position to a straightened position. 35 40 45

24. In combination, an electric switch for controlling a load circuit, a centrifugal device, a motor for rotating said centrifugal device, and a trip free mechanism for transmitting force from said centrifugal device to 50 said switch to close the same comprising means adapted to respond to the electrical condition of the circuit controlled by the switch for rendering said mechanism ineffective to hold the switch closed. 55

25. In combination, an electric switch, a centrifugal operating device therefor comprising weights movable in response to rotation from a greater to a less effective position, a motor for rotating said weights, and 60 mechanism for transmitting force from said weights to said switch to close the same, said mechanism comprising a toggle for compensating the loss in effectiveness of said weights. 65

In witness whereof I have hereunto set my hand this 7th day of June, 1922.

LUDVIG S. WALLE.
